UNITED STATES PATENT OFFICE.

ERNEST WILDHABER, OF BROOKLYN, NEW YORK, ASSIGNOR TO NILES-BEMENT-POND COMPANY, OF NEW YORK, N. Y., A CORPORATION OF NEW JERSEY.

HOB.

Application filed December 30, 1922. Serial No. 609,943.

To all whom it may concern:

Be it known that I, ERNEST WILDHABER, a citizen of the Republic of Switzerland, residing at Brooklyn, in the county of 5 Kings and State of New York, have invented certain new and useful Improvements in Hobs, of which the following is a specification.

My invention relates to hobs and particularly to form hobs for shaping milling cutters.

One object of my invention is to provide a form hob having cutting edges inclined with respect to the hob axis for cutting straight or helical flutes on a blank.

Another object of my invention is to provide a form hob having teeth arranged in the form of a thread on a cylindrical body portion; the teeth having cutting edges inclined with respect to the hob axis and an end tooth of the hob having a finishing cutting edge.

Another object of my invention is to provide a form hob of the above indicated 25 character that shall have a pitch different from the circular pitch taken on the outside diameter of the blank to be cut.

A further object of my invention is to provide a form hob having teeth arranged 30 in the form of a thread and having a pitch larger than the pitch taken at the outside diameter of the blank to be cut, the teeth having cutting edges inclined with respect to the hob axis and an end tooth of each hob having a finishing cutting edge.

The term "form hob", as used in this specification, is intended to cover a hob having a finishing cutting edge which cuts its own profile on the teeth of the blank being 40 shaped. In hobs generally in use at the present time, the teeth of a blank are shaped by a generating operation. In a generating operation, a number of the teeth on a hob serve to effect the finishing cut on each 45 tooth of the blank. In a form hob, one tooth effects a finishing cut on a whole face of each blank tooth. Reference may be made to my copending application Serial No. 609,941 filed December 30, 1922 for a further discussion of the term "form hob".

Form hobs have been constructed heretofore wherein the cutting faces on the hob teeth have been arranged perpendicularly to the axis of the hob. A finishing cutting 55 edge is formed on the end tooth of the hob.

The hob, when operating on a blank, is positioned with respect to the blank so that the cutting edge on the finishing cutting tooth is aligned with a radial blank plane which is drawn perpendicularly to the hob axis. When so positioned with respect to a blank, the hob cuts teeth having radially arranged cutting faces. However, hobs having cutting faces arranged perpendicularly to the axis thereof are not suitable for cutting spiral flutes or teeth having high cutting faces.

In a hob constructed in accordance with my invention, the teeth are arranged in the form of a thread on a cylindrical body portion. The pitch of the hob teeth is preferably made larger than the circular pitch of the blank taken on the outside diameter of the blank. The above statement refers especially to straight flutes on the blank. 70 In the case of spiral flutes on the blank, the pitch of the hob would be made larger than the corresponding pitch at a right angle to the flutes. A finishing cutting tooth is located at one end of the hob and such 75 finishing tooth is provided with a finishing edge. The finishing edge is located in a radial blank plane which is not perpendicular to the axis of the hob. A hob, when so constructed and so positioned with respect to 80 the blank, serves to cut teeth having radially arranged cutting faces. The hob may be provided with undercut cutting faces on the teeth thereof and may be constructed to cut spiral flutes on the blank or cut 85 teeth having undercut cutting faces. As above set forth, the pitch of the hob should be larger than the pitch at the outside diameter of the blank. The hob described and claimed in this application is 90 also shown and described in my copending application Serial No. 609,942 filed December 30, 1922.

In the accompanying drawing:

Figure 1 is a diagrammatic view illustrating a hob having a pitch different from the blank pitch taken on the outside diameter of the blank.

Fig. 2 is a plan view of the hob and blank shown in Fig. 1.

A hob having the cutting edges of the teeth perpendicular to the hob axis has some drawbacks which limit its utility. For example, a hob of this type is not suitable for cutting teeth of a very large size inas- 110

much as the helicoidal action of the hob tends to cut a convex surface on the teeth. Moreover, if such a hob were used to form spiral flutes, a convex profile of a comparatively sharp curvature, would be formed on the blank teeth. The operation of a hob of this type in cutting spiral flutes may be compared with the grinding of spiral flutes by means of the plain side of a grinding wheel. It is well known that it is impossible to grind spiral flutes with the plain side of a grinding wheel and that only convex surfaces are produced which spoil the milling cutter being ground. In order to grind spiral flutes it is essential to provide a suitable conical grinding wheel. In accordance with the above reasoning, it is apparent that in order to cut spiral flutes, it is desirable to provide a hob having substantially straight cutting edges which are inclined with respect to the axis of the hob. Thus, it is necessary, or at least desirable, to provide a hob having cutting edges which are angularly disposed with respect to a blank radius located in a plane perpendicular to the hob axis. The operation of such a form hob is very similar to the operation of a conical grinding wheel or milling cutter.

Referring to the accompanying drawing, a hob 1 is shown having teeth 2 formed on a cylindrical body portion 3. The hob is adapted to rotate in a counter-clockwise direction on an axis XY and is provided with a finishing tooth 4. It will be noted that the cutting edges on the teeth 2 are inclined with respect to the axis of the hob and are accordingly suitable for cutting spiral flutes on a milling cutter blank. The hob is shown in engagement with a blank 5 having teeth 6. The blank is shown rotating on an axis C in a clockwise direction.

The inclined cutting edges of the hob 1 are obtained by forming the hob with a pitch p which is different from the pitch taken on the outside diameter of the blank 5. The pitch p is larger than the circular pitch taken on the outside diameter of the blank 5. In this regard, it may be noted that the pitch of a hob having the cutting faces disposed perpendicularly to the hob axis is exactly equal to the pitch taken on the outside diameter of the blank being operated upon. In the case of spiral flutes on the blank, the pitch referred to must be taken perpendicularly to the flutes.

Assuming the tooth 4 to be in a finishing position and the radial line C-7 to make an angle α with a radial plane perpendicular to the axis of the hob, the pitch of the rack corresponding to the hob 1 may be obtained in the manner disclosed in my application Serial No. 609,941 filed December 30, 1922. A line is drawn through a point 7 on the outside diameter of the blank 5 perpendicularly to the radial line C-7. Such line intersects the line CZ drawn perpendicularly to the axis of the hob at a point 8. A line MN drawn through the point 8 parallel to the line of movement of the hob 1 is the pitch line for a rack corresponding to the hob. Thus, the pitch of the rack corresponding to the circular pitch on the circle having a radius equal to C-8 is p .

If a rack or a hob corresponding thereto is constructed as above indicated and is fed to the left as shown in Fig. 1 of the drawing, the teeth to the right of the finishing position shown in Fig. 1 will not interfere with the radial profile of the blank tooth. The hob is illustrated in position to finish one blank tooth as heretofore set forth. However, if the rolling motion between the hob and blank were continued to the left beyond the illustrated position then an involute would be generated. The generation of an involute would start at the position illustrated in the drawing and when the tooth 4 was cutting along the line C-7.

The position of the tooth 4 is illustrated in Fig. 1 of the drawing as a limiting position when the hob is provided with a pitch along the line MN and corresponding to the circular pitch at a radius C-8. If the pitch should be made larger and the pitch line placed farther away from the axis of the blank, the positions of the rack or hob teeth to the right of the illustrated position would not interfere with the radial face of the blank tooth taken along a line C-7. Moreover, in such case the illustrated position would not be the limiting position and the position at which the generating of an involute would start. However, the changing of the pitch in such manner would form larger flutes on the blank and accordingly would weaken the teeth of the blank.

Thus, as above set forth, by using a form hob corresponding to a rack having a pitch different from the pitch on the outside diameter of the blank, it is possible to provide a hob with inclined cutting edges. Such cutting edges, as heretofore set forth, operate in a manner similar to a cone grinding wheel when operating on cutters having helical flutes.

It should be understood that such changes and modifications may be made in my invention as fall within the limits of the appended claims.

What I claim is:

1. A hob having one finishing cutting edge and comprising teeth arranged in the form of a thread on a cylindrical body portion, the teeth having substantially straight cutting edges inclined with respect to the hob axis and the finishing cutting edge being located at the end of the hob.
2. A hob comprising teeth arranged in

- the form of a thread on a cylindrical body portion, the teeth having substantially straight cutting edges inclined with respect to the hob axis and the pitch of the hob differing from the pitch of the teeth on the blank to be cut.
3. A hob comprising undercut teeth arranged in the form of a thread on a cylindrical body member, the teeth having substantially straight cutting edges inclined with respect to the hob axis and the pitch of the hob differing from the pitch of the teeth on the blank to be cut.
4. A form hob having one finishing cutting edge and comprising teeth arranged in the form of a thread on a cylindrical body member for cutting teeth having spiral flutes on a blank, the finishing cutting edge being located at one end of the hob.
5. A form hob having one finishing cutting edge and comprising teeth arranged in the form of a thread on a cylindrical body member for cutting spiral flutes to form undercut teeth on a blank, the finishing cutting edge being located at one end of the hob.
6. A form hob having one finishing cutting edge and comprising teeth arranged in the form of a thread on a cylindrical body member for cutting spiral flutes to form undercut teeth on a blank, the teeth having substantially straight cutting edges inclined with respect to the blank axis.
7. A form hob having teeth arranged in the form of a thread, the teeth having substantially straight cutting edges inclined with respect to the hob axis and the pitch of the hob being larger than the pitch at the outside diameter of the blank.
8. A form hob having one finishing cutting edge and comprising teeth arranged in the form of a thread, the teeth having substantially straight cutting edges inclined with respect to the hob axis and the finishing cutting edge being located outside or inside an end tooth on the hob according to the value of the hob pitch relative to the value of the pitch at the outside diameter of the blank.

In testimony whereof, I hereto affix my **50** signature.

ERNEST WILDHABER.
